Primary Examiner — Freda S Nunn*(74) Attorney, Agent, or Firm* — Rader, Fishman & Grauer PLLC(57) **CLAIM**

The ornamental design for a wireless data transmitter, as shown and described.

DESCRIPTION

FIG. 1 is a front, top, right perspective view of a wireless data transmitter showing our new design;

FIG. 2 is a rear, bottom, left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

Broken lines shown in the drawings illustrate portions of the wireless data transmitter and form no part of the claimed design.
